COAXIAL TRANSMISSION LINE

**Kenneth A. Young, Waban, Mass., assignor to
Raytheon Manufacturing Company, Newton,
Mass., a corporation of Delaware**

Application July 5, 1944, Serial No. 543,582

4 Claims. (Cl. 178—44)

1

This invention relates to coaxial transmission lines, and more particularly to an improved means for supporting the central conductor of such lines in proper alignment with the surrounding outer conductor.

It is among the objects of this invention to provide a supporting structure for the center conductor of a coaxial line which will provide greater mechanical rigidity than structures heretofore proposed and which will also possess superior electrical characteristics.

It has heretofore been proposed as disclosed in the copending application of Joseph Goldsmith, Serial Number 522,489, filed February 15, 1944, to provide a supporting connection between the outer conductor and the central conductor of a coaxial transmission line, which supporting connection is comprised entirely of metallic elements positioned within the circumference of the outer conductor.

It is among the objects of the present invention to provide an improved construction having greater mechanical rigidity, which is easier to manufacture, which will possess greater mechanical strength and rigidity, and which will permit the transmission line to transmit a much broader range of frequencies.

The above and other objects of the invention will be made apparent to those skilled in the art from a consideration of the following detailed description taken in conjunction with the accompanying drawing in which:

Fig. 1 shows a longitudinal section through a portion of a coaxial transmission line constructed in accordance with the present invention.

Fig. 2 shows a transverse section taken on line 2—2 of Fig. 1; and

Fig. 3 shows a set of curves illustrating certain operating characteristics of the invention.

Referring to the drawing, reference numeral 1 indicates a section of the outer tubular conductor of a coaxial transmission line having a central conductor 2. The central conductor is supported relative to the outer conductor by means of a pair of branch connectors 3 and 4 of conductive material and of substantially the same diameter as the central conductor 2. The outer ends of each of the branch connectors 3 and 4 have a curved surface conforming to the interior surface of the outer conductor 1 to which they are rigidly attached by means of screws 5 and 6. The joints between the curved ends of the branch connectors 3 and 4 and interior surface of the outer tubular conductor 1 may be made highly conductive and the rigidity of the structure improved by solder-

ing or otherwise integrally connecting the branch connectors to the interior surface of the outer conductor after the parts have been secured in position by screws 5 and 6. The branch connectors 3 and 4 are preferably formed integrally with sleeves 7 and 8, respectively, which sleeves are shrunk or otherwise rigidly fixed upon the conductor 2. The branch connectors 3 and 4 are so spaced upon the central conductor 2 that the distance between the center lines thereof is approximately equal to

$$\frac{3\lambda}{4}$$

15 where λ is the length of the waves on the transmission line. The length of the sleeves 7 and 8 is approximately

$$\frac{\lambda}{2}$$

20 In operation since the connectors 3 and 4 are spaced at a distance of

$$\frac{3\lambda}{4}$$

25 the reflections from these connectors will be out of phase by an amount corresponding to a phase difference of 180° and, therefore, the reflections will approximately cancel at frequencies corresponding to λ .

30 The sleeves 7 and 8 provide half wave length transformers extending along the inner conductor 2 for a distance of approximately

$$\frac{\lambda}{4}$$

35 on either side of the center line of the connectors 3 and 4. This permits transmission over a broad wave band.

The function of the sleeves 7 and 8 may be best 40 understood if the operation of the structure be considered without these transformers. In the absence of the transformers 7 and 8 and assuming that the conductor 2 be directly connected to the outer conductor 1 by branch connectors 3 and 4 of the same diameter as the central conductor 2, and that the branch connectors 3 and 4 are spaced at

$$\frac{3\lambda}{4}$$

45 or any odd multiple of one-quarter wave length, then the reflections from the branch connectors 3 and 4 will cancel at frequencies corresponding closely to λ . Such a construction would be rather 55 selective and frequencies somewhat greater or less

than those corresponding to λ would not be readily transmitted without loss.

It will be seen that an increase in the length of the waves passing through the transmission line would correspond to a decrease in the electrical spacing between the branch connectors 3 and 4. In other words if λ be increased to λ_1 and the linear distance between the center lines of the connectors 3 and 4 remains the same, then this distance in terms of λ_1 would be less than

$$\frac{3\lambda_1}{4}$$

Accordingly, if this spacing is critical at

$$\frac{3\lambda}{4}$$

then the system is necessarily highly selective since any slight variation in λ would correspond to a change in the spacing of the connectors. By the provision of the sleeves 7 and 8, the spacing between the connectors 3 and 4 is less critical at

$$\frac{3\lambda}{4}$$

Accordingly, the range of frequencies which the structure will pass is greatly increased, corresponding to a variation of around 10 per cent of a given wave length λ when the connectors 3 and 4 are spaced at approximately

$$\frac{3\lambda}{4}$$

The length of the transformers 7 and 8 is likewise not highly critical at

$$\frac{\lambda}{2}$$

so that the frequencies passed by the structure are not restricted to a narrow band on this account. In the determination of the diameter of the transformers 7 and 8 it will be simpler in most instances for those skilled in the art to determine these by direct electrical measurement of reflections in any particular frequency range rather than to determine them by analysis. The transformer diameter is not highly critical but may vary within a few hundredths of an inch for any given wave band. In the set of curves shown in Fig. 3, the ordinates represent the standing wave ratio in power (herein denoted by r^2) resulting from reflections and the abscissas represent the wave length in centimeters. The curve a shows the values of r^2 for values of λ between 9.4 and 10.4 cm. where r is the standing wave ratio in voltage due to reflections, and r^2 is the standing wave ratio in power. As an example of a commercially successful embodiment of the invention in a line operating at frequencies corresponding to a wave length centered at 9.8 cm. the following dimensions were used. The internal diameter of conductor 1 was 1.527 inches; the diameter of the central conductor was $\frac{1}{8}$ of an inch; the outer diameter of the transformers 7 and 8 was 0.835 inch and the length was 1.950 inches. Small variations in the diameter of the transformers were not important as may be seen from Fig. 3 in which the curve a represents the characteristics of the system when the transformer diameter is 0.825 inch and the curve b represents the characteristics when the transformer diameter is 0.835 inch. In both of the instances represented by the curves a and b, the connectors 3 and 4 were spaced at a distance of 7.5 cm. and angularly displaced at 90°. Some

of the advantages of the invention are obtained when the connectors 3 and 4 are not angularly displaced or are displaced at angles other than 90°. Curve c represents the characteristics of the system when, with other factors the same as in curve b, the angular displacement of the connectors 3 and 4 was 180°. In this case the frequency sensitivity was increased although the system still permitted transmission over a frequency band sufficiently wide for some purposes. It is therefore preferred to position the connectors 3 and 4 at an angle of about 90° since this construction permits the passage of a wider wave band. Also the construction provides a more rigid support for the central conductor than where the connectors are positioned in line or displaced at an angle of 180°. In practice as many pairs of supports 3 and 4 may be disposed along a length of a coaxial line as are necessary to support the central conductor in rigid alignment with the outer tubular conductor. Each pair of supports gives great rigidity to a substantial length of transmission line, each pair being electrically balanced to cancel the electrical discontinuity to the connectors 3 and 4.

It will be obvious that many departures may be made from the specific details shown. For example, the transformers 7 and 8 may be made integrally with the conductor 2 rather than separately therefrom and the branch connectors 3 and 4 may be made integrally with portions 7 and 8 or may be made separately therefrom and rigidly secured thereto in any suitable manner.

While there is herein shown a particular embodiment of the invention other embodiments and modifications within the scope of the appended claims will be apparent to those skilled in the art from a consideration of the structure shown and the teachings hereof.

40. What is claimed is:

1. An electric transmission line for transmitting high frequency electric waves including a tubular conductor, a central conductor coaxial with said tubular conductor, means for maintaining said conductors in fixed spaced relation comprising a first metallic connector between said conductors, a second metallic connector spaced from said first connector by a distance approximately equal to three-fourths of the length of the waves on said line and positioned at right angles thereto, said central conductor having enlargements providing transformers adjacent each of said connectors, said enlargements extending on each side of the center lines of said connectors for a distance approximately equal to one-quarter of the length of the waves on said line.

2. An electric transmission line for transmitting high frequency electric waves including a tubular conductor, a central conductor coaxial with said tubular conductor, and means for maintaining said conductors in fixed spaced relation comprising a pair of T-shaped connectors of conductive material each including a sleeve portion surrounding said central conductor and rigidly fixed thereto and a portion projecting from said sleeve portion and extending to and rigidly connected with said outer conductor.

3. An electric transmission line for transmitting high frequency electric waves including a tubular conductor, a central conductor coaxial with said tubular conductor, means for maintaining said conductors in fixed spaced relation comprising a pair of T-shaped connectors of conductive material each including a sleeve portion surrounding said central conductor and rigidly

fixed thereto and a portion projecting from said sleeve portion and extending to and rigidly connected with said outer conductor, said T-shaped connectors being so spaced that the distance between the center lines of said projecting portions is approximately equal to three-fourths of the length of the waves on said line.

4. An electric transmission line for transmitting high frequency electric waves including a tubular conductor, a central conductor coaxial 10 with said tubular conductor, means for maintaining said conductors in fixed spaced relation comprising a pair of T-shaped connectors of conductive material each including a sleeve portion surrounding said central conductor and rigidly 15 fixed thereto and a portion projecting from said sleeve portion and extending to and rigidly connected with said outer conductor, said T-shaped connectors being so spaced that the distance be-

tween the center lines of said projecting portions is approximately equal to three-fourths of the length of the waves on said line, said projecting portions extending in planes normal to the axis of said central conductor and angularly displaced relative to each other.
